UNITED STATES PATENT OFFICE.

CHARLES OSKAR BERGMARK, OF CHICAGO, ILLINOIS.

FEED-WATER REGULATOR.

Specification of Letters Patent. Patented June 14, 1910.

961,577.

Application filed September 15, 1909. Serial No. 517,806.

To all whom it may concern:

Be it known that I, CHARLES O. BERGMARK, a citizen of the United States, and a resident of Chicago, in the county of Cook and State of Illinois, have invented a new and Improved Feed-Water Regulator, of which the following is a full, clear, and exact description.

The object of the invention is to provide a new and improved feed water regulator, more especially designed for regulating the flow of the feed water into a boiler or the like, and arranged to maintain water in the boiler at an approximately constant level.

For the purpose mentioned, use is made of a controlling device in the feed water supply and normally open, and an automatic means connected with the said controlling device and actuated by pressures of steam derived from the boiler, the pressures when equal holding the said controlling device open to allow the boiler to fill with water, and when the latter reaches a predetermined level in the boiler then one steam pressure is reduced by condensation of the steam and the said controlling device is closed.

A practical embodiment of the invention is represented in the accompanying drawing forming a part of this specification, in which the figure is a sectional side elevation of the feed water regulator as applied to a boiler and its feed pipe.

A boiler A, of any approved construction, is supplied with water by means of a feed pipe B connected with a pump or other source of water supply. The flow of the water through the feed pipe B is controlled by a valve C of any approved construction, and normally open by the action of a spring D pressing a rod E pivotally connected with an arm E' attached to the stem C' of the valve C. The rod E is mounted to slide in a lug F' of a frame F attached to the casing C² of the valve C, and the spring D above mentioned rests with one end on the lug F' and presses at the other end on a nut E² secured on the rod E, to hold the valve C normally open. By adjusting the nut E² the tension of the spring D can be regulated.

A diaphragm chamber G is attached to or forms a part of the frame F, and is provided with a diaphragm H secured to the stem C', dividing the chamber G into compartments G', G², of which the compartment G' is connected by a pipe I with a pipe J leading to the steam compartment A' of the boiler

A. The compartment G² of the diaphragm chamber G is connected by a pipe K with the upper end of a condensation chamber L, connected at its lower end by a pipe N 60 with the water compartment A² of the boiler A. Into the upper end of the condensation chamber L leads a channel L', connected at its lower end with a pipe O extending into the upper portion of a controlling chamber 65 P, connected at its bottom by a pipe P' with the pipe N and hence with the water compartment A² of the boiler A. Into the top of the controlling chamber P also opens a short pipe J² extending from a tee J' at 70 attached to the pipe J, and through which tee J' extends the pipe O, as plainly indicated in the drawing.

The controlling chamber P is arranged opposite the boiler A, while the condensation chamber L extends above the same and the pipe O extends into the controlling chamber P such a distance that its lower end is level with the intended level of the water in the boiler A. By the construction described 80 and shown the controlling chamber P is filled with water from the boiler A to the same level as that of the water in the boiler A, and the water in the controlling chamber P rises and falls with the water in the 85 boiler A. Now as long as the water in the controlling chamber P uncovers the lower end of the pipe O, it is evident that steam passes by way of the pipe J, tee J', pipe J², upper end of chamber P, pipe O, channel L', condensation chamber L and pipe K into the compartment G² of the diaphragm chamber G, so that the pressure on both sides of the diaphragm H is approximately equal as both chambers G' and G² are now directly connected 90 with the steam compartment A' of the boiler A, and hence the spring D holds the valve C in normal open position, whereby water flows into the boiler A. Now as the water rises in the boiler A it also rises 100 in the chamber P and finally submerges the lower end of the pipe O. When this takes place, the compartment G² of the diaphragm chamber G is cut off from the steam compartment A' of the boiler A, and as the 105 steam in the condensation chamber L now condenses, the pressure is reduced in the said chamber L and in the compartment G², so that preponderance of pressure in the chamber G' forces the diaphragm H to the left, thus moving the valve C into a closed position and thereby cutting off the water sup- 110

ply from the boiler A. When the level of the water in the boiler A and the chamber P falls until the lower end of the pipe O is uncovered, then steam from the boiler A can 5 again pass by way of the pipe O and channel L' into the condensation chamber L, by way of the pipe K into the compartment G², thus equalizing the pressures on the diaphragm H, to allow the spring D to again 10 move the valve C into an open position.

From the foregoing, it will be seen that by the arrangement described, the valve C is held normally open for filling the boiler A with water, and when the predetermined 15 level is reached the valve C is automatically closed as the preponderance of pressure in the compartment G' causes movement to the left of the diaphragm H, as before explained, and when the pressures are again 20 equalized in the chambers G', G², the diaphragm returns to normal position and with it the valve C by the action of the spring D.

Having thus described my invention, I claim as new and desire to secure by Letters Patent:

1. A feed water regulator, comprising a feed water supply, a valve in the water supply having a stem, a spring for normally holding the valve open, a diaphragm chamber having a diaphragm connected with the valve stem, the said diaphragm dividing the chamber into compartments, a pipe leading from the steam compartment of the boiler, a pipe connecting said pipe with one 30 of the compartments of the diaphragm chamber, a condensation chamber connected at its upper end with the other compartment of the diaphragm chamber and connected at its lower end with the water compartment of the boiler, a controlling chamber connected at its upper end with the pipe leading from the steam compartment of the boiler, and at its lower end with the water compartment of the boiler, and a pipe extending into the upper end of the controlling chamber and connected with the upper 35 part of the condensation chamber.

2. A feed water regulator, comprising a feed water pipe connected with the boiler, a normally open valve in the feed water pipe, a diaphragm chamber having a diaphragm connected with said valve, the said diaphragm dividing the chamber into compartments, a pipe connected with the steam compartment of the boiler, a pipe leading from said pipe to one of said compartments of the diaphragm chamber, a condensation chamber connected at one end by a pipe with the other compartment of said diaphragm chamber, a pipe connecting the other end of said condensation chamber with the water compartment of the boiler, a controlling chamber connected at one end with the pipe leading from the condensation chamber to

the water compartment of the boiler, a tee 65 attached to the pipe leading to the steam compartment of the boiler and connected with the other end of the controlling chamber, and a pipe connected with the condensation chamber and extending through the 70 said tee into the controlling chamber to a point corresponding to the intended level of the water in the boiler.

3. A feed water regulator, comprising a feed supply, a normally open valve in the 75 feed water supply, a diaphragm chamber having a diaphragm connected with said valve, the said diaphragm dividing the chamber into compartments, of which one is directly connected with the steam chamber in the boiler, a condensation chamber connected at its upper end with the other compartment of the said diaphragm chamber, and connected at its lower end with the water compartment of the boiler, the said 80 condensation chamber having a channel leading into the upper end thereof, a controlling chamber connected at the top with the steam compartment of the boiler and at the bottom with the water compartment of the 85 boiler, and a pipe connected with the lower end of said channel of the condensation chamber and extending into the said controlling chamber to a point corresponding to the intended level of the water in the boiler. 90

4. A feed water regulator comprising a feed water pipe connected with the boiler, a valve in the feed water pipe and provided with a stem, an arm on the stem of said valve, a rod connected with said arm, and 100 mounted to slide, a spring on said arm, means for regulating the tension of said spring, a diaphragm chamber having a diaphragm dividing the chamber into compartments, one of said compartments being 105 directly connected with the steam compartment of the boiler, the said valve stem extending into the other compartment of the diaphragm chamber and connected with the diaphragm, and means controlled by the fall 110 and rise of water in the boiler for connecting and disconnecting the last mentioned compartment of the diaphragm chamber with the steam compartment of the boiler, the said spring permitting the valve to close 115 when the said compartment of the diaphragm chamber is cut off from the steam compartment of the boiler, and holding the valve open when both compartments of the diaphragm chamber are directly connected 120 with the steam compartment of the boiler.

In testimony whereof I have signed my name to this specification in the presence of two subscribing witnesses.
